UNITED STATES PATENT OFFICE.

WILLIAM G. HUTCHISON, OF VALPARAISO, INDIANA.

VENTILATOR.

1,234,031.

Specification of Letters Patent.

Patented July 17, 1917.

Application filed October 24, 1916. Serial No. 127,375.

To all whom it may concern:

Be it known that I, WILLIAM G. HUTCHISON, a citizen of the United States, and a resident of Valparaiso, in the county of Porter and State of Indiana, have made certain new and useful Improvements in Ventilators, of which the following is a specification.

My invention is an improvement in ventilators, and has for its object to provide a device of the character specified especially adapted for use with railroad cars, wherein a casing is provided which may be arranged in the ventilator openings at the tops of the cars, the casing being open at the inner side and at its ends, and having a series of longitudinally extending baffle plates arranged in approximately parallel and overlapping relation at one end of the ventilator casing to form a series of passages extending longitudinally of the casing, and wherein a door is hinged to the opposite end to open outward, and a partition is arranged at the inner side of the door between the same and the baffle plates.

In the drawings:

Figure 1 is a horizontal section through a ventilator in place.

Fig. 2 is an enlarged detail of Fig. 1.

Fig. 3 is a perspective view showing the door.

Fig. 4 is a section on the line 4—4 of Fig. 1.

Fig. 5 is a top plan view of one of the regulating valves.

The present embodiment of the invention is shown in connection with a car body 1, the ventilator being arranged in the opening 2, and the casing of the ventilator is of a size to fit closely within the opening. This casing is substantially U-shaped in cross section, comprising an arched body 3 and side walls 4, and the casing is open at its inner side and at one end, as shown.

The other end of the casing is partially closed by a transverse partition 5, said partition being at the open side of the casing, and leaving an outlet or passage 6 between the body of the casing and the partition.

A door 7 is hinged at this point as indicated at 8, to open outward, and a longitudinally extending partition 9 is arranged at the inner side of the door, the partition extending somewhat less than half the length of the casing.

A series of pairs of baffle plates 10 and 10^a is arranged in the casing at the opposite end from the door, the members of the pairs being approximately parallel and spaced apart from each other to form passages between the same.

The pairs overlap, as shown in Figs. 1 and 2, the pair at the end of the casing being nearer the body and overlapping the succeeding pair in spaced relation, thus forming another passage between the adjacent members of the adjacent pairs.

In the present instance three (3) pairs of plates are provided, and each pair overlaps the adjacent ends of the succeeding pair, the last pair overlapping the adjacent end of the partition 9.

As shown in Fig. 4, each plate 10—10^a is provided with laterally extending flanges 11 at its side edges, and the flanges 11 of each plate 10 fit against the inner faces of the side walls 4 of the casing, while the flanges 11 of the plates 10^a fit against the inner faces of the flanges 11 of the adjacent plate 10.

An angle plate 12 is secured to the inner face of each side wall of the casing, and these angle plates secure the flanges 11 of the plates 10 and 10^a to the casing. The angle plates are secured to the side walls by means of rivets 13 or the like, with one portion extending laterally inward above the baffle plates, to prevent the entrance of rain and the like.

As shown in Figs. 1 and 2, a stop plate 14 extends longitudinally from the inner end of the partition 9 and the door 7 is hinged to this stop plate. When the ventilator is in place the stop plate laps against the outer face of the car, and the outermost plate 10 at the opposite end of the casing is extended beyond the said end, as indicated at 15, to perform a like service at the said end.

A strip 16 of perforate material, as for instance wire, cloth, is arranged over the ends of the passages between the baffle plates, the said strip preventing the entrance of cinders and the like.

In use, the ventilator is arranged as shown in Fig. 1, with the door 7 at the rear end of the casing. When the car is traveling, the air will enter at the end of the casing remote from the door, and will pass out at the door opening 6, acting in the manner of an injector to draw the foul air from the car.

through the passages between the baffle plates.

The door 7 will regulate the force of the air traveling through the casing, and it will be noticed that the said door is hung to normally swing partially open when the car is in motion and to swing shut when the car is stopped.

Means is also provided for automatically regulating the amount of air passing from the car through passages between the plates 10 and 10^a of the pairs and the plates 10^a and 10 of the adjacent pairs. Each of the said means is a valve or damper 17, which is provided with pintles or journal pins 18 journaled in the sides of the casing 3-4. A coil spring 19 encircles one of these pintles, and acts normally to hold the valve in open position. A buffer 20 is arranged adjacent to each valve, against which the valve opens, and these buffers are connected to the plates 10^a in any suitable manner. In operation, when the passage of air through the openings between the plates 10 and 10^a, and 10^a and 10 becomes too great, the gates or valves 17 will be lifted or partially lifted to lessen the extent of the passages, and the said gates will eventually close as indicated by the dotted lines in Fig. 2.

I claim:—

1. In a ventilator, a series of pairs of longitudinally extending approximately parallel baffle plates, said plates being spaced apart and the pairs being arranged with the outermost pairs overlapping the innermost pairs, and with the outermost pair at the inlet end of the casing, valves for closing the passages between the plates, springs normally holding the valves open, and a buffer for supporting each valve in an inclined position to permit the air to have access thereto to close the same. 30 35 40

2. In a ventilator, a series of pairs of longitudinally extending approximately parallel baffle plates, said plates being spaced apart and the pairs being arranged with the outermost pairs overlapping the innermost pairs, and with the outermost pair at the inlet end of the casing. 45

3. In a ventilator, a series of spaced baffle plates arranged in lapping relation to form a series of passages between the plates, valves for closing the passages between the plates, springs normally holding the valves open, and a buffer for supporting each valve in inclined position to permit the air to have access thereto to close the same. 50 55

WILLIAM G. HUTCHISON.
